CASTING DEVICE

Lawren E. Broyles and Everett J. Pittenger,
Chico, Calif.

Application July 7, 1944, Serial No. 543,906

10 Claims. (Cl. 22—5)

This invention relates in general to a stereotype casting device, and in particular the invention is directed to, and it is an object to provide, a novel stereotype casting device arranged for use with conventional type-casting machines whereby to simplify and facilitate the preparation of stereotype mats.

Another object of the invention is to provide a stereotype casting device which includes unique safety features arranged to prevent molten metal from escaping the device when subjected to the pressure of the stream of molten type metal from the mold and mouthpiece of the type-casting machine.

A further object of this invention is to provide a stereotype mat-casting device which comprises, with a body or "stick" formed to cooperatively engage with the table opening of a type-casting machine, a lock-up slide disposed in longitudinally slideable relation in a matrix receiving channel in the body, the channel being approximately the same length as said slide and open only at one end, the slide seating against a matrix in said channel and having a casting opening or slot therein registering with said matrix, and a normally fixed but releasable cross slide engaging in holding relation across one end of the lock-up slide at the open end of the channel; said lock-up slide projecting beyond the corresponding face of the body and arranged for inward movement upon engagement by the movable mold of the machine so as to urge said slide into positive lock-up relation with the matrix.

A further object of the invention is to produce a simple and inexpensive device, and yet one which will be exceedingly effective for the purpose for which it is designed.

These objects we accomplish by means of such structure and relative arrangement of parts as will fully appear by a perusal of the following specification and claims.

In the drawing similar characters of reference indicate corresponding parts in the several views:

Figure 1 is a plan view of our improved stereotype casting device.

Figure 2 is a longitudinal section illustrating the lock-up slide and cross slide in operative position.

Figure 3 is a similar view, but showing the cross slide retracted from the path of the lock-up slide, and the latter partially withdrawn from the body.

Figure 4 is a front end view of the device disposed in upwardly facing position.

Figure 5 is a cross section on line 5—5 of Fig. 2.

Figure 6 is a front end view of the device in the inverted position which it occupies when mounted on the type casting machine.

Referring now more particularly to the characters of reference on the drawing, the device comprises an elongated body or "stick" 1, which is notched inwardly from the face 2 along the outer longitudinal edges thereof as at 3.

Between the notches 3 the body 1 is formed with a relatively shallow channel 4 which is open at one end to the front end of the body; the other end of said channel being closed by an end wall 5. The channel 4 is of a width and length to receive, in seated relation in the bottom thereof, a flat stereotype matrix 6 which carries the impression 7 in the outer face thereof; said matrix being pre-formed, as usual, from a relatively heavy strip of mat paper.

A lock-up slide 8 slidably engages in the channel 4 from the initially open end thereof, said slide being the same length as the channel, and being formed with a longitudinally extending slot 9 of a size and configuration to expose the working portion of the face of the stereotype matrix 6. In other words, the slide 8 engages only about the marginal portion of the matrix 6.

As clearly shown in Fig. 5, the slide 8 is provided, as at 10, with a dovetail fit in the channel 4.

The height of the slide 8 is such that when the inner face of the slide is disposed in engagement with the matrix 6, the outer face 11 of said slide is disposed in a horizontal plane outwardly of the horizontal plane of face 2 of the body 1. In addition to such outward projection of the slide, as above, said slide is capable of limited inward movement by virtue of the dovetail mounting thereof. These structural features are important, for the reason as will hereinafter appear.

When the slide 8 is fully engaged in the channel 4 it is normally held against accidental escape by means of a cross slide 12 dovetailed, as at 13, into the front end of the body 1 for sliding movement from a position overlapping the initially open end of said channel, as shown in Fig. 2, to a position clear of the channel 4, as shown in Fig. 3. The cross slide 12 is formed with a vertically elongated slot 13 through which a retaining screw 14 projects; the inner end of said screw being threaded into the body, while the outer end of said screw is provided with a thumb engaging head 15.

In use of the above described stereotype casting device, the same is disposed in an inverted position, as shown in Fig. 6, and engaged in cooperative relation with the opening 16 in the table

17 of a conventional type casting machine (not shown), such as the "Ludlow"; the device being held against lateral displacement by engagement of the notches 3 with corresponding portions of the table 17 on opposite sides of opening 16. As so positioned the device is engaged from above and thus held against vertical displacement by means of a lock-down lever unit (not shown) but which is also conventional on type casting machines.

As so mounted the casting device is ready for use. Thereafter the mold, together with included mouthpiece of the type casting machine, as indicated diagrammatically at 18, is raised until the upper face of said mold forcefully engages with the outer face of the lock-up slide 8. As the face 11 of said lock-up slide projects outwardly beyond the face 2 of the body, and as said slide is capable of limited inward movement, the forceful engagement of the mold 18 with said slide pushes the latter tightly against the matrix for the casting operation. This provides a lock-up on the matrix so tight that there is no possibility of molten metal flowing past the matrix. This is a valuable safety feature, which is also enhanced by the dovetail mounting of the cross slide 13; which prevents any possible escape of the molten metal in the direction of the operator.

With the several parts engaged as above, molten metal is introduced from the mold 18 through the opening 8 and against the matrix 6, to form the desired stereotype mat. After the molten metal has been introduced and has been permitted to harden, the body 1 is removed from the type casting machine, and the stereotype mat is withdrawn from the slide 8; the inner walls 19 of said slide slightly diverging outwardly to facilitate removal of the formed mat.

In order to remove and replace the matrix 6 it is only necessary to unloosen the screw 14, shift the cross slide 12 clear of channel 4, and to then withdraw the slide 8 and the matrix 6 from said channel.

From the foregoing description it will be readily seen that we have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described our invention, what we claim as new and useful and desire to secure by Letters Patent is:

1. A stereotype mat casting device comprising a body formed with a strip matrix receiving channel open to one face thereof, said channel being initially open at one end, a lock-up slide engaged in the channel from said one end, means retaining the slide against outward escape from the channel, said lock-up slide engaging the marginal portions of a matrix in the bottom of the channel and being open between said marginal portions, and releasable means normally preventing removal of the slide from the channel; said last named means comprising a cross slide mounted on the body for movement from a position clear of to a position intersecting the channel at said one open end thereof.

2. A mat casting device as in claim 1 in which said cross slide includes an elongated slot therethrough, and a headed locking screw projecting through the slot and threaded into the body.

3. A stereotype mat casting device comprising a body formed with a strip matrix receiving channel open to one face thereof, said channel being initially open at one end, a lock-up slide engaged in loose fitting dovetail relation in the channel from said one end thereof, said lock-up slide seating against the marginal portions of a matrix in the bottom of the channel and being open between said marginal portions, and releasable means normally preventing removal of the lock-up slide from the channel.

4. A stereotype mat casting device comprising a body formed with a strip matrix receiving channel open to one face thereof, said channel being initially open at one end, a lock-up slide engaged in loose fitting dovetail relation in the channel from said one end thereof, said lock-up slide seating against the marginal portions of a matrix in the bottom of the channel and being open between said marginal portions, and releasable means normally preventing removal of the lock-up slide from the channel; the lock-up slide projecting outwardly beyond said one face of the body and being capable of limited inward movement into clamping relation with said marginal portions of the matrix.

5. A stereotype mat casting device comprising a body formed with a strip matrix receiving channel open to one face thereof, said channel being initially open at one end, a lock-up slide engaged in dovetail relation in the channel from said one end thereof, said lock-up slide seating against the marginal portions of a matrix in the bottom of the channel and being open between said marginal portions, and a cross slide mounted on the body for movement from a position clear of to a position intersecting the channel at said one open end thereof.

6. A stereotype mat casting device comprising a body formed with a strip matrix receiving channel open to one face thereof, said channel being initially open at one end, a lock-up slide engaged in dovetail relation in the channel from said one end thereof, said lock-up slide seating against the marginal portions of a matrix in the bottom of the channel and being open between said marginal portions, and a cross slide mounted on the body for movement from a position clear of to a position intersecting the channel at said one open end thereof; said cross slide being slidably mounted on the body in dovetail relation.

7. A stereotype mat casting device comprising a body formed with a strip matrix receiving channel open to one face thereof, said channel being initially open at one end, a lock-up slide engaged in dovetail relation in the channel from said one end thereof, said lock-up slide seating against the marginal portions of a matrix in the bottom of the channel and being open between said marginal portions, and a cross slide mounted on the body for movement from a position clear of to a position intersecting the channel at said one open end thereof; said cross slide being slidably mounted on the body in dovetail relation, and including an elongated slot therethrough, and a headed locking screw projecting through the slot and threaded into the body.

8. A stereotype mat casting device comprising a body formed with a strip matrix receiving channel open to one face thereof, said channel being initially open at one end, a lock-up slide engaged in dovetail relation in the channel from said one end thereof, said lock-up slide seating against the marginal portions of a matrix in the

bottom of the channel and being open between said marginal portions, a cross slide mounted in dovetail relation on the body for sliding movement between a position clear of the channel to a position intersecting said one end thereof, and means to releasably lock the cross slide in either position; the lock-up slide projecting outwardly beyond said one face of the body and being capable of limited inward movement into clamping relation with said marginal portions of the matrix.

9. A self-contained stereotype mold comprising a body provided with a matrix receiving channel open to one face of such body, two opposite sides of said channel being provided with dove tail shaped grooves, a lock up slide, two outer edges of said slide being of dove tail shape and being

fitted in relatively loose relation in the dove tail shaped grooves in the body whereby a matrix may be interposed between the slide and the bottom of the channel in the body with the slide overlapping the marginal edges of the matrix, the slide having an open slot to expose the matrix therethrough, the outer edges of the slide projecting beyond the adjacent face of the body whereby pressure may be exerted against such projecting edges to force the loose fitted slide into tight engagement with the matrix.

10. A device as in claim 9 in which at least two sides of the slot in the lock up slide diverge outwardly whereby to permit the ready release 15 of the stereotype casting.
